UNITED STATES PATENT OFFICE

HOWARD KNIGHT, OF PROVIDENCE, RHODE ISLAND, ASSIGNOR TO LIVERMORE AND KNIGHT COMPANY, OF PROVIDENCE, RHODE ISLAND, A CORPORATION OF RHODE ISLAND

ADVERTISING DEVICE

Application filed August 19, 1931. Serial No. 557,981.

This invention relates to improvements in advertising devices. More especially it has to do with a device which attracts the attention of the observer by producing an effect of motion.

but it is intended that the patent shall cover by suitable expression in the appended claims whatever features of patentable novelty exist in the invention disclosed.

In the drawings:

Figures 1, 2 and 3 are front, rear and side elevations, respectively, of a device embodying the invention;

Figure 4 is a plan of the same;

Figure 5 is an enlarged elevation of a portion of the front or picture panel;

Figure 6 is an elevation (in perspective) of a section taken as on line 6-6 of Figure 5;

Figure 7 is an elevation in section on line 7-7 of Figure 4; and

Figure 8 is a perspective showing how the device as a whole may be dissembled and arranged for shipment.

Referring more particularly to the drawings, the picture panel 1 is made from opaque stock such as sheet metal, veneered wood, cardboard or the like which is not frangible like the usual translucent or transparent panel heretofore used. The sheet is cut to any preferred configuration and has depicted thereon any desired advertising matter together with some fanciful picture or design, a portion of which represents an object in motion. In the illustrated example the picture is that of a man holding a tumbler 2 of sparkling beverage. The effect of effervescence of this beverage is produced by providing perforations or holes 3 in the panel within the region defined by the outline of the tumbler and causing light rays to emanate intermittently through these holes.

This intermittent or variable light transmission is produced by a rotatable screen 4 mounted close by the back side of the panel 1 and opposite the perforations 3. The screen comprises a sheet of translucent paper 5 which has alternate clear bands 5a and varied opaque bands 5b running diagonally across the sheet. When the latter is arranged as the wall of a cylinder these bands extend

5 It is a principal object of this invention to provide a simple device of this character with a minimum number of elements which can be made individually at small expense, shipped in a dissembled condition in a compact package and readily assembled for display purposes.

10 Heretofore, so far as I am aware, apparatus for producing illuminated motion effects has comprised a translucent panel or light transmitting picture element made of glass or other frangible material. Another object of the invention is to eliminate such material and employ a perforated opaque panel which is not easily fractured or marred.

15 This panel may conveniently take the form of a piece of heavy cardboard alone or such a board with a sheet of paper secured to it. On either the board or its superimposed paper surface is depicted the advertisement comprising a fanciful design having a portion thereof representing an object in motion. This portion is provided with perforations or holes through which light rays pass intermittently by virtue of a rotatable screen having alternate

20 translucent and opaque portions. This screen surrounds a source of light, preferably an ordinary electric lamp, and is rotated by heat from the latter.

25 It is a feature of the invention to provide as a support for this lamp and screen a collapsible standard that is attached to the rear of the picture panel and can lie flatwise thereagainst when collapsed. This standard 30 when folded in use supports both the lamp and picture panel in an upright position and constitutes a partial enclosure for the screen.

35 The best mode in which I have contemplated applying the principles of my invention is shown in the accompanying drawings

helically on its surface. The top and bottom edges of this sheet are secured to light metal rings 6 the upper one of which frictionally engages the flange edge 7a of a light metal plate 7 at whose center is a hole through which projects a glass cup or socket 8. The body of the plate is cut so as to permit portions of it to be bent and thereby form vanes 7b.

- 10 The screen 4 is mounted on a bent rod 9 whose upper end engages the glass socket 8 and whose lower end loops around a lamp socket 10. The rod is so shaped and proportioned that when an ordinary electric lamp 11 is screwed into its socket 10 and the screen is mounted on the rod, the lamp and screen are substantially in axial alignment with the bulb encased within the screen. The heat waves from the lamp act on the vanes 15 7b to cause rotation of the screen and as the helical bands 5a, 5b move past the holes 3 in the picture panel, the light rays from the lamp, as respects each hole, are intermittently cut off. The effect from the observer's viewpoint is to make it appear as though bubbles 20 were forming in the liquid and rising to the surface thereof, thereby producing the desired effervescent appearance of the beverage.
- 25 The picture panel 1 and the lamp 11 are supported in upright positions by a novel standard 12 which may also be conveniently formed of sheet stock such as cardboard or the like. The body portion 12a of this standard is attached to the rear face of the picture panel, from which wing members 12b are bent backwards at right angles to the panel. The rear edge portions 12c of the wings are bent toward one another into parallelism with the body portion and serve to reinforce the wings. A section 12d of the body portion is cut along three sides, on two of which a pair of ears (12f and 12g) are also cut from the respective wings. This section 12d is then bent downward about its lower attached edge 12e to form a shelf whose outer end 12d' is bent back upon itself. This turned down end carries one pair of ears 12f which are inserted through suitable transverse slots in the wings, the horizontal shelf having the other pair of ears 12g which similarly enter horizontal slots in the wings. The shelf has a hole through which the stem 10a of the lamp socket projects downward, the socket and looped end of the rod 9 being clamped to the shelf by a collar 13 which tightly engages the stem 10a.
- 40 The opening 12h formed in the body portion of the standard is arranged opposite the portion of the picture which is to represent a body in motion, in this illustration, the tumbler 2. If the picture is printed directly on the surface of the panel the latter is perforated as before noted, but a preferable form is to print the picture on a rela-

tively thin opaque sheet 14 and then apply this sheet to the surface of the panel. When this is done it is possible to perforate a large number of such sheets in one operation of the punch. The picture panel, when being cut out to the desired configuration, is formed with an opening 1a sufficiently large to embrace the outline of the tumbler when the printed sheet 14 is applied to the panel. There is a distinct advantage gained by employing this cut-out opening 1a on the panel board and using the thinner perforated opaque sheet 14 because when a relatively thick panel is perforated with holes, the divergence of the light rays passing through them is somewhat limited, necessitating the observer standing almost directly in front of the holes to get the full benefit of the motion effect. By using the opening in the panel and providing the holes in the relatively thin opaque sheet 14, the divergence of the light rays is greatly increased and the desired effect may be experienced by observers standing at various positions on the front side of the panel.

45 The device as constructed may be shipped in a comparatively flat package. The shelf of the section 12d standard is left unfolded in the body thereof and the two wings are folded flatwise thereover, as shown in Figure 8. The variated sheet 5 and its light metal rings 6 which form the wall of the cylindrical screen may be flattened and laid on the panel as is also the separated top plate 7. The bent rod 9 and lamp socket 10 are likewise placed on the panel, and with all the parts thus arranged the whole may be wrapped as a relatively thin flat package. The lamp is not supplied with the device since any lamp of suitable wattage can be 50 easily purchased by the user. When received by the latter the cylinder parts are assembled, the standard bent or folded as already described, the lamp socket and rod clamped to the shelf and a bulb inserted in the socket. The cylinder is then mounted on the rod and the light turned on. Very promptly the screen begins to revolve and the desired motion effect is produced. The wings of the standard and the opaqueness of the panel and picture sheet prevent any light rays from passing to the front of the panel other than through the perforations 55 3. And the intermittent cutting off of these rays by the opaque bands of the screen, produces such a varied lighting of the holes that the desired motion effect is attained.

60 It is to be understood that the picture here shown and the nature and arrangement of the perforations are merely illustrative, and that other pictures and different shapes, sizes and arrangement of holes may be employed without departing from the essence 65 of the invention.

I claim:

1. An advertising device comprising, in combination, an opaque panel having a picture on one side thereof with a portion representing a body in motion, and having holes through said portion; a second panel attached to the opposite side of said first panel, having a section of said second panel bent backward to provide an opening opposite said perforations; a source of light supported on said bent back section; and means also supported on said section for effecting intermittent transmittal of light rays from said source through said holes.
- 15 2. An advertising device comprising, in combination, an opaque panel having a picture on one side thereof with a portion representing a body in motion, and having holes through said portion; a second panel attached to the opposite side of said first panel, having a section of said second panel bent backward to provide an opening opposite said perforations and a horizontal shelf; other sections of said second panel being 20 folded rearward and connected to said shelf as a support therefor and adapted to support the first said panel in an upright position; and means mounted on said shelf and adapted to effect the intermittent transmittal of light rays through said holes.
